UNITED STATES PATENT OFFICE.

IRVING CHARLES WOODWARD, OF, SYRACUSE, NEW YORK.

METHOD OF FORMING SCREW THREADS.

Application filed December 15, 1922. Serial No. 607,120.

To all whom it may concern:

Be it known that I, IRVING CHARLES WOODWARD, a citizen of the United States of America, and a resident of Syracuse, county 5 of Onondaga, and State of New York, have invented a new and useful Improvement in Methods of Forming Screw Threads, of which the following is a specification.

This invention relates to screw threads, 10 and its object is to provide a method of forming a screw thread which will insure a perfect and tight fit with a coacting thread.

Figure 1 of the drawings shows, in section, a nut having an imperfect or incomplete thread, as formed by the first step of the process.

Figure 2 illustrates the method of completing the thread.

Figure 3 shows the same section of a nut 20 as in Figure 1, but with the thread as it would appear after performing the second step of the process.

The completed thread as shown in the drawing is standard in every respect as to 25 form, but may, when formed by the present process, be more perfect in respect to surface engagement with a coacting thread also of standard form and pitch. In many uses of coacting threaded members it is desired to 30 have the threads fit perfectly and under sufficient pressure all along their surfaces to effectively resist accidental motion between the coacting threaded members. It is found that this purpose may be attained 35 most perfectly by a process which involves the first step of only partly forming a thread and the second step of completing the thread by application of the partly threaded article to the mate with which it coacts. The 40 thread may be first partly formed as illustrated in Figure 1 by rolling or preferably cutting a groove 2, forming the interdental of the first step thread, the apex 3 of this interdental being of proper form for the 45 finished thread, but the space above the apex being narrower than will be the case in the finished thread. This step of the process leaves the thread 4 with a finished base 5 of the correct angle, but an incomplete crest 6 wider than is required for the finished thread 50 and not rising as high from the base as does the finished crest. The cross sectional area

of the unfinished thread, however, is equal to the desired cross sectional area of the finished thread.

The second step in the process consists in applying the article having the incomplete thread to a mate 7, preferably of harder material and provided with a finished coacting thread 8. This finished coacting thread 60 serves to crowd the material at the crest 6 of the unfinished thread upwardly so as to bring this crest to the required height and to a form properly conforming to the angles at the sides of the base of the thread. The 65 material of the unfinished thread is in this manner caused to compensate for any imperfections in the finished thread 8, and to firmly engage the finished thread all along its surface and with sufficient pressure to 70 prevent accidental motion between the coacting threaded members, provided the first step in the process of forming the thread is correctly carried out so as to leave an imperfect thread but one of cross sectional 75 area equal to that desired in the finished thread 9.

I claim:

1. The method of forming a screw thread which consists in first partially forming the 80 thread by cutting or rolling a groove in the part to be threaded, the bottom of said groove being left in the required form for the finished thread, but the top of the groove being of less width than that required for 85 the finished thread, and the second step of completing the thread by a squeezing and sliding action along the sides of the thread whereby the upper portion thereof is forced upwardly into a finished crest.

2. The process of forming a screw thread which consists in first partly forming a 90 thread so as to provide a base for the thread of finished form but leaving the crest unfinished and wider and of less height than in the finished thread, and second, forming the crest of the thread by applying the partly threaded article to another article 95 made of harder material and having a finished thread whereby the process of forming 100 the thread is completed by a sliding and squeezing action of the finished thread along the sides of the unfinished thread.

3. The process of forming a screw thread

which consists in first forming on an article to be threaded, an incomplete thread having a uniform pitch and sufficient volume to form a full thread, but being imperfect as to height and width at the crest, and second, forcing said imperfect thread into engagement with a mating part having a com-

pleted thread whereby the mating part serves as a forming device for completing the imperfect thread by sliding pressure 10 along the sides of the imperfect thread.

Signed at Syracuse this seventh day of December, 1922.

IRVING CHARLES WOODWARD.
